CLAIM

The ornamental design for a tool box for construction machine as shown and described.

DESCRIPTION

FIG. 1 is a perspective view of a tool box for construction machine showing our new design;

FIG. 2 is a front view thereof;

FIG. 3 is a rear view thereof;

FIG. 4 is a left side view thereof, the right side view being a mirror image;

FIG. 5 is a top view thereof;

FIG. 6 is a bottom view thereof;

FIG. 7 is a perspective view thereof in an alternate position;

FIG. 8 is a front view thereof;

FIG. 9 is a rear view thereof;

FIG. 10 is a left side view thereof, the right side view being a mirror image;

FIG. 11 is a top view thereof;

FIG. 12 is a bottom view thereof; and,

(Continued)

FIG. 13 is a cross-sectional view thereof taken along line 13-13 of FIG. 8.
